UNITED STATES PATENT OFFICE.

WILLIAM STANLEY McLEWEE, OF YARDLEY, PENNSYLVANIA.

DESIGN FOR A GLOBE FOR GAS-LIGHTS.

SPECIFICATION forming part of Design No. 36,869, dated April 5, 1904.

Application filed February 6, 1904. Serial No. 192,455. Term of patent 14 years.

To all whom it may concern:

Be it known that I, WILLIAM STANLEY McLEWEE, a citizen of the United States, residing at Yardley, in the county of Bucks and State 5 of Pennsylvania, have invented a new, original, and ornamental Design for a Globe for Gas-Lights, of which the following is a specification, reference being had to the accompanying drawings, forming part thereof.

Figure 1 is a side elevation of a globe for

gas-lights, showing my new design. Fig. 2 is a plan view of the same.

What I claim as new, and desire to secure by Letters Patent, is—

The ornamental design for a globe for gas-lights, as shown.

WILLIAM STANLEY McLEWEE.
